APPARATUS FOR THE UNIFORM DISTRIBUTION OF TOBACCO IN THE SPREADER OF A CIGARETTE-MAKING MACHINE

Alexander Herbert Klüx, Dresden, Germany, assignor to Universelle Cigarettenmaschinen-Fabrik J. C. Müller & Co., Dresden, Germany

Application January 28, 1932, Serial No. 589,500
In Germany February 6, 1931

20 Claims. (Cl. 131—39)

Methods have already been proposed for delivering the cut tobacco to the tobacco spreaders of cigarette-making machines by pneumatic means. Although it is possible in this manner to replenish the amount of tobacco which is being used, it does not solve the problem of distributing this quantity of tobacco during its passage from the separator into the spreader, in such manner that it forms an extremely even layer which extends over the entire tobacco spreader as far as the walls. This is, however, necessary in order to obtain a uniform performance of the spreader.

According to this invention an impact surface is placed in the path of the delivery air, which impact surface corresponds to the length of the spreader rollers.

These surfaces are preferably reciprocated transversely to the longitudinal direction of the rollers varying the tobacco receiving space of the spreader. The surface may, however, be curved in such a way that the tobacco particles which arrive thereon are flung off downwards at an angle of dispersion, and this angle can be so adjusted that it covers the entire surface in question of the tobacco spreader.

In order to bring about a uniform distribution of the tobacco on the impact surface it is advisable to fit in front of the surface a wedge-shaped distributor against which the stream of tobacco impinges. This distributor can be adjusted in such manner that its apex is always directed towards the middle of the on-coming stream of tobacco.

To enable the invention to be fully understood it will now be described with reference to the accompanying drawing, wherein:—

Fig. 1 is a vertical longitudinal section.

Fig. 2 is a plan.

Figs. 3 and 4 are detailed views.

The current of air carrying the tobacco is conducted into the separator 2 by means of the pipe 1. Between the pipe 1 and the separator 2 there is inserted a funnel-shaped member 3, the wide end of which is directed towards the separator 2. In the separator 2 there is arranged a metal plate 4 which extends over the entire width of the separator. To the metal plate 4, the horizontal part 4' of which overlaps the upper end 3' of the wide end of the funnel-shaped member, there are attached two pins 5 which are passed into slots 6' of the upper wall 6 of the separator. The upper end of the pins 5 serve as pivots for the connecting rods 7, the other ends of which are pivotally attached to the crank pins 8 of discs 9. The discs 9 are mounted on a shaft

10 which is mounted in a bearing 11. The latter is attached to a projection 12 of the distributor. On the shaft 10 there is also mounted a sprocket wheel 13 which is driven by a chain 14. On the metal plate 4 there is also attached a distributor 15 of triangular cross section, the deflecting sides of which are concave as shown in Figs. 1, 3 and 4. Figs. 3 and 4 are, respectively, sections on the lines 3—3 or 4—4 of Fig. 1.

The on-coming tobacco first of all impinges on the distributor 15 and is thereby distributed over the entire plate.

From the plate 4 a part of the tobacco flows downwards, and a part is scattered in the manner indicated in Fig. 1, so that it is uniformly distributed. Now, by the rotation of the shaft 10 the plate 4 is moved continually to and fro between the position indicated by full lines and that indicated by dotted lines, so that the tobacco is distributed over the entire surface x of the tobacco spreader 16.

In order that the distribution of the tobacco may be as uniform as possible, it is absolutely necessary that the distributor member 15 should be exactly in the middle of the oncoming stream 80 of tobacco. As shown for instance in Fig. 2, the pipe 1' may, however, be curved before it discharges into the distributor 2. In this case the stream of tobacco would not be directed towards the middle of the tobacco distributor if the latter 85 were exactly in the middle of the separator. Now in order in such cases to make it possible for the distributor member 15 to be located exactly in the middle of the oncoming stream of tobacco it is arranged adjustably on the plate 4. For this purpose the plate 4 is provided with a transverse slot 17 through which the adjusting screw 18 of the distributor member 15 protrudes. Now, by adjusting the distributor member so that it comes into position in the middle of the stream of tobacco, it is easily possible to procure a uniform distribution of the tobacco over the surface x of the tobacco spreader, even if, owing to bends in the pipes or the like, the stream of tobacco arrives obliquely in the separator.

Having thus described the nature of the said invention and the best means I know of carrying the same into practical effect, I claim:—

1. Apparatus for the uniform distribution of tobacco in the spreader of a cigarette making machine comprising pneumatic delivery means for the tobacco, an impact surface located in the path of the current of air delivering the tobacco and means for varying the distance of said impact surface from said pneumatic delivery means.

2. An apparatus for the uniform distribution of tobacco in the spreader of a cigarette making machine comprising pneumatic delivery means, a curved impact surface located in the path of the tobacco delivered by said delivery means and means for reciprocating said impact surface. 5
3. An apparatus for the uniform distribution of material comprising pneumatic delivery means, spreader rollers for said material, an impact surface having a width substantially the same as the length of said rollers and means for moving said impact surface transversely to the longitudinal axes of said rollers. 10
4. An apparatus for the uniform distribution of material comprising pneumatic delivery means, spreader rollers for said material, an impact surface having a width substantially the same as the length of said rollers and means for reciprocating said impact surface. 15
- 20 5. An apparatus for the uniform distribution of tobacco in the spreader of a cigarette making machine comprising delivery means discharging the tobacco, a curved plate intersecting said tobacco and means for reciprocating said curved plate. 25
6. An apparatus for the uniform distribution of material comprising means for discharging the material to be distributed, an impact surface against which said material strikes and a distributor cooperating with said impact surface to aid in distributing the material over the entire surface of said impact surface. 30
7. An apparatus for the uniform distribution of material comprising means for discharging the material to be distributed, an impact surface against which said material strikes, a distributor cooperating with said impact surface to aid in distributing the material over the entire surface of said impact surface and means for reciprocating said impact surface. 35
8. An apparatus for the uniform distribution of material comprising means discharging the material to be distributed, an impact surface against which said material strikes and a wedge-shaped distributor associated with said impact surface to spread the material substantially over the entire surface of said impact surface. 40
9. An apparatus for the uniform distribution of tobacco in the spreader of a cigarette making machine comprising spreader rollers, means for delivering tobacco in a constant stream, a plate against which said stream of tobacco strikes and a wedge-shaped surface mounted upon said plate to distribute the tobacco substantially throughout the entire area of said plate. 45
10. An apparatus for the uniform distribution of tobacco in the spreader of a cigarette making machine comprising spreader rollers, means for discharging a stream of tobacco, a plate against which said stream of tobacco strikes and which directs the tobacco towards said spreader rollers and an adjustable distributor associated with said plate to aid in directing the tobacco substantially over the entire area of said plate. 50
- 60 11. An apparatus for the uniform distribution of tobacco in the spreader of a cigarette making machine comprising spreader rollers, means for discharging a stream of tobacco, a plate against which said stream of tobacco strikes and which directs the tobacco towards said spreader rollers, an adjustable distributor associated with said plate to aid in directing the tobacco substantially over the entire area of said plate and means for reciprocating said plate towards and from said discharging means. 65
12. An apparatus for the uniform distribution of tobacco in the spreader of a cigarette making machine comprising means for discharging a stream of tobacco, spreader rollers and wedge-shaped deflecting means for said stream of tobacco directing said tobacco towards said spreader rollers. 80
13. An apparatus for the uniform distribution of tobacco in the spreader of a cigarette making machine comprising spreader rollers, means for discharging a stream of tobacco, wedge-shaped deflecting means located in the path of said stream of tobacco to direct the tobacco towards said spreader rollers and the apex of said deflecting means being substantially opposite the center of said stream of tobacco. 85
14. An apparatus for the uniform distribution of tobacco in the spreader of a cigarette making machine comprising spreader rollers, means for discharging a stream of tobacco, wedge-shaped deflecting means located in the path of said stream of tobacco to direct the tobacco towards said spreader rollers, the apex of said deflecting means being substantially opposite the center of said stream of tobacco and means for adjusting said deflector transversely of the path of said stream of tobacco. 90
15. An apparatus for the uniform distribution of tobacco in the spreader of a cigarette making machine comprising spreader rollers, means for discharging a stream of tobacco, wedge-shaped deflecting means located in the path of said stream of tobacco to direct the tobacco towards said spreader rollers, the apex of said deflecting means being substantially opposite the center of said stream of tobacco, means for adjusting said deflector transversely of the path of said stream of tobacco and means for reciprocating said deflector in the path of said stream of tobacco. 95
16. An apparatus for the uniform distribution of tobacco in the spreader of a cigarette making machine comprising a casing, spreader rollers disposed within said casing, means for discharging a stream of tobacco into said casing, a curved plate within said casing located in the path of said stream of tobacco and cam means for reciprocating said plate in the path of said stream of tobacco. 100
17. An apparatus for the uniform distribution of tobacco in the spreader of a cigarette making machine comprising a casing, spreader rollers mounted within said casing, means for discharging a stream of tobacco into said casing, a curved plate mounted in said casing extending transversely of said stream of tobacco and having a width substantially equal to the length of said spreader rollers, a wedge-shaped distributor adjustably mounted upon said plate and located at substantially the center of said stream of tobacco in order to deflect said tobacco throughout substantially the entire area of said plate and means for reciprocating said plate in a direction parallel to the direction of said stream of tobacco. 105
18. An apparatus for the uniform distribution of tobacco in the spreader of a cigarette making machine comprising a casing, spreader rollers mounted within said casing, means for discharging a stream of tobacco into said casing, a curved plate mounted in said casing extending transversely of said stream of tobacco and having a width substantially equal to the length of said spreader rollers, a wedge-shaped distributor adjustably mounted upon said plate and located at substantially the center of said stream of tobacco 110
- 135
- 140
- 145
- 150

in order to deflect said tobacco throughout substantially the entire area of said plate, means for reciprocating said plate in a direction parallel to the direction of said stream of tobacco, means for slidably mounting said plate within said casing and means for reciprocating said plate.

19. An apparatus for the uniform distribution in the spreader of a cigarette making machine comprising a casing, a delivery pipe for a stream 10 of tobacco, a cone-shaped pipe connecting said casing to said delivery pipe, spreader rollers within said casing, a plate located within said casing and transversely of the path of said stream of tobacco, a pair of pins secured to said plate and

extending through slots in said casing, rods connected to said pins and cam means for reciprocating said rods and thereby reciprocating said plate within said casing so as to secure a more uniform distribution of said tobacco in the vicinity of said spreader rollers. 80

20. An apparatus for the uniform distribution of the tobacco in the spreader of a cigarette making machine comprising pneumatic delivery means for said tobacco and an impact surface 85 located in the path of the current of air delivering said tobacco so as to sub-divide said tobacco uniformly.
